UNITED STATES PATENT OFFICE

ANDREW EPPLER, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE

1,108,560.

Specification of Letters Patent. Patented Aug. 23, 1914.

Application filed August 8, 1908. Serial No. 447,542.

To all whom it may concern:

Be it known that I, ANDREW EPPLER, a citizen of the United States, residing at Boston, in the county of Suffolk and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The present invention relates to inseam shoe sewing machines, and is intended primarily as an improvement on inseam shoe sewing machines of that class which form a chain-stitch and which are provided with a curved hook needle entering the shoe from the outside, and with a stitch-setting take-up operating to pull the last-formed loop tightly around the shank of the needle while the needle is in the work. An example of this class of machine is the well-known Goodyear welt and turn shoe sewing machine, the construction and mode of operation of which is disclosed with substantial accuracy in the patent to French and Meyer, No. 412,704. As will be obvious to those skilled in the art, however, certain features of the present invention are equally applicable to other types of inseam shoe sewing machines, and it is to be understood that except as defined in the claims the several features of the present invention are not limited to use in any particular type of inseam shoe sewing machine.

It is customary in chain-stitch inseam shoe sewing machines to give the needle a forward movement or dip during the feed of the shoe to prevent an objectionable pull being exerted by the loop of needle thread on the needle, which pull would be liable to break the thread or the needle and would interfere with the proper manipulation of the shoe by the operator. This forward movement or dip of the needle is necessarily constant throughout the entire sewing operation, and while it effectively prevents an objectionable pull of the needle in sewing along the sides of a shoe, it does not prevent a pull upon the needle when the shoe is swung in passing around the toe.

An object of the present invention is to provide means whereby a sufficient tension is maintained on the loop of needle thread to keep the loop in the barb of the needle, and

at the same time relieve the needle of any objectionable pull at all times during the sewing operation which would tend to injure the thread or break the needle or interfere with the manipulation of the shoe.

With this object in view, a feature of the present invention consists in the provision of means for actuating the needle during its retracting stroke to exert a strain on the thread sufficient to tighten the preceding loop and means for yieldingly supporting the needle during the feed, arranged to exert a less strain on the thread. In the preferred embodiment of this feature of the invention, the means for actuating the needle is arranged to positively actuate the needle through the whole of its retracting stroke to tighten the preceding loop. The needle is then released from its retracting mechanism and is supported under light spring pressure during the feed of the work.

In chain-stitch inseam shoe sewing machines in which the needle operates from the outside and the awl enters the channel of the shoe, difficulty has been experienced in arranging the awl so that it would pierce the work in a path substantially concentric with that of the needle, and at the same time strike at the bottom of the channel.

An object of the present invention is to provide an awl in this class of machines which will pierce the work in a path of substantially the same curvature as that of the needle, and which will strike the work at the bottom of the channel without requiring any objectionable tipping movement of the shoe sufficient to bring the seam in an improper position.

With this object in view a feature of the present invention contemplates the provision in a machine of the class referred to of a curved awl mounted to move about an axis eccentric to the axis of the needle in a path of smaller radius than that of the needle and substantially tangent to the path of the needle at the point where the needle pierces the work. Awl mechanisms have heretofore been devised in which the awl is mounted to move about an axis concentric to that of the needle, but in actual practice it has been found that an awl mounted concentric with the needle is liable to strike the sole back of the channel so that an objectionable tipping of the shoe is required to cause the awl to clear the sole. By provid-

ing an awl mounted eccentric to the needle and movable in a path of smaller radius the awl clears the sole and engages the work at the bottom of the channel while the shoe is held in position to locate the seam properly. A curved awl which is mounted eccentric to the needle and which moves in a path of smaller radius than that of the needle is especially advantageous when used 10 in connection with a machine of the class above referred to, provided with a needle piercing the shoe from the outside. Such an awl can, however, be advantageously used in other classes of chain-stitch inseam sewing machines, as will be obvious to those skilled in the art. Accordingly this feature of the invention is not limited, except as defined in the claims, to use in any particular type of chain-stitch shoe sewing machine. 20 When the awl is used in connection with a machine having a needle which pierces the shoe from the outside, the axis of the awl is preferably located at the rear and below the axis of the needle. 25 Other features of the present invention consist in an improved construction and arrangement of the looper mechanism by which the thread is placed in the barb of the needle, and in certain devices, combinations 30 and arrangements of the parts tending to improve and simplify the operation of inseam shoe sewing machines and enable them to operate with certainty at a high rate of speed and without liability of breakage of 35 the parts. The advantages of these devices, combinations and arrangements of parts will be obvious to those skilled in the art from the following description. 40 The several features of the present invention will be clearly understood from an inspection of the accompanying drawings, in which—

Figure 1 is a view in front elevation of a welt sewing machine embodying the same in their preferred form. Fig. 2 is a view in 45 side elevation of the machine looking from the right. Fig. 3 is a view in side elevation of the machine looking from the left. Fig. 4 is a sectional elevation taken upon a vertical plane just at the right of the needle as viewed in Fig. 1. Fig. 5 is a detail view 50 illustrating in front elevation the feed slide, the parts supported thereby, and their actuating mechanism. Fig. 6 is a view in side elevation of the parts illustrated in Fig. 5. Fig. 7 is a view similar to Fig. 5 but with 55 certain parts removed or broken away, and with a portion of the mechanism shown in section. Fig. 8 is a detail sectional view of the parts illustrated in Fig. 5, taken on a plane indicated by the line 8—8 of said figure. Fig. 9 is a detail view illustrating the feed slide in front elevation and showing the guides and supporting bracket for the 60 feed slide in dotted lines. Fig. 10 is a view 65

in side elevation of the parts illustrated in Fig. 9. Fig. 11 is a view in front elevation of the feed slide and its supporting bracket and guides. Fig. 12 is a view in end elevation of the parts illustrated in Fig. 11. Fig. 70 13 is a detail sectional plan view illustrating particularly the relation of the feed slide to its actuating lever. Fig. 14 is a detail plan view of the slide which forms a portion of the mechanism for actuating the looper. Fig. 15 is a view in side elevation of the 75 slide illustrated in Fig. 14. Figs. 16 and 17 are detail views illustrating the connections between the needle segment and its actuating lever, Fig. 16 illustrating the position of the parts while the needle is being positively actuated, and Fig. 17 illustrating the position of the parts while the needle is yieldingly supported under light spring pressure, to allow the needle to be pulled forward when the shoe is swung. Fig. 18 is a detail view 80 on an enlarged scale of the mechanism illustrated in Figs. 16 and 17, but looking in the opposite direction. Fig. 19 is a diagrammatic view illustrating the paths of motion 85 of the needle and awl and their relation to the work operated upon. Fig. 20 is a diagrammatic view illustrating the manner in which the thread pulls upon the needle when the shoe is swung in sewing round the 90 toe.

The machine illustrated in the drawings is provided with a curved hook needle, a needle guide, a looper, a thread arm, a takeup, an auxiliary takeup, a channel 100 guide, a welt guide, a back rest, back rest and welt guide slides, and a tension device, all having the same general arrangement and mode of operation, except as herein-after described, as the corresponding parts 105 of the Goodyear welt and turn machine disclosed in Patent No. 412,704.

The needle 1 is secured in the usual manner to a needle segment 2 pivotally mounted in a stationary portion of the machine frame and connected by a link 3 to a cam actuated lever 4. To enable the needle to be positively actuated during its retracting stroke, so as to exert a positive pull on the loop of needle thread sufficient to shorten the preceding loop, and thereafter be yieldingly supported under light spring tension during the feed of the work, the link 3 is connected to the cam actuated lever 4 as follows. The lever 4 is provided at its forward end with a slot in which is mounted a block 5, to which the link 3 is pivoted. This block, during the retracting stroke of the needle, is held in the upper end of its slot by means of a latch which as shown consists of a block 6 mounted to slide in a guideway on the lever 4 at right angles to the slot in which the block 5 is mounted. The latch block 6 is held in position on the lever 4 by means of a bolt 7 passing through a slot in the 110 115 120 125 130

block, and the block is pressed toward the block 5 by means of a coiled spring 8 interposed between the block 6 and an abutment 9 on the lever. The block 6 is provided at its forward end with a notch or shoulder which engages the block 5. During the retracting stroke of the needle the latch block 6 is in engagement with the block 5, and to permit the latch block to be moved 10 out of engagement therewith at the end of the retracting stroke, the lower end of the link 3, which projects below the block 5, is provided with an abutment screw or pin 10, the construction being such that after the 15 needle completes its retracting stroke and shortens the preceding loop, the abutment 10 strikes the block 6 and moves it out of engagement with the block 5. When the block 5 is released, it is supported on the 20 lever 4 by means of a spring 11 surrounding a rod 12 adjustably secured in the lever 4 and extending longitudinally of the slot. The upper end of the rod 12 forms a stop to limit the movement of the block 5 in its 25 slot, and thereby determines the amount of yielding movement permitted to the needle. The tension of the spring 11 is such that during the feeding of the work a light yielding strain is exerted upon the loop of the 30 needle thread sufficient to hold the thread in the barb of the needle, but not sufficient to injure the needle or thread, or interfere with the proper feeding or manipulation of the shoe.

35 The advantages secured by the construction above described, whereby the needle is yieldingly supported during the feed of the work, will be clearly understood from an inspection of Fig. 20, which indicates diagrammatically the manner in which the distance from the last needle hole to the barb of the needle increases when the shoe is swung in passing around the toe.

40 The needle guide is mounted and actuated in substantially the same manner as in certain prior chain stitch shoe sewing machines with the exception that the actuating mechanism is more simple and compact. The needle guide, indicated at 13, is secured to or 45 formed integral with one end of a shaft which extends axially through the hollow pivot shaft of the needle segment. To the other end of the needle guide shaft is secured a segment 14 with which a segment 15 50 meshes secured to the forward end of a cam actuated lever 16. The needle guide is thus actuated positively and directly through a cam actuated lever and can be operated with certainty and at a high rate of speed. The 55 thread finger or arm, indicated at 17, is also arranged and actuated as in prior machines, with the exception that its thread engaging end is arranged to rise higher from the work 60 and thereby avoid striking the channel flap. 65 This movement of the thread arm is per-

mitted by the arrangement of the looper, as will be hereinafter explained. The thread arm is secured upon one end of a shaft mounted in the stationary head of the machine, and to the other end of this shaft is 70 secured an arm 18. The arm 18 is connected by a link 19 to the forward end of a cam actuated lever 20.

75 The looper, which lays the thread into the barb of the needle, is indicated at 21. This looper is provided with a shank which is received in a cylindrical socket formed in the lower end of an arm 22, the connection between the looper shank and the arm being such that the looper can be adjusted vertically. The shank of the looper is held in the arm by means of a clamping screw 23. The arm 22 is pivoted midway its length to a block 24 secured to the forward end of a cam actuated slide 25. The slide 25 is arranged 80 above the needle and in a plane parallel with the plane of the needle so that the reciprocating movements of the slide impart forward and rearward movements to the looper. The movements of the looper at right angles to the plane of the needle are produced by oscillating the arm 22, the movements of the looper due to the reciprocation of the slide and the oscillation of the arm acting to carry the thread around the needle and lay it in 85 the barb. The upper end of the arm 22 is provided with a socket in which a rod 26 is received. This rod is provided at its upper end with a socket or bearing which receives a rod 27 secured to an arm 28 projecting 90 from a rock shaft 29 arranged parallel with the slide 25. The rod 26 is free to slide in the socket in the upper end of the arm 22, and the rod 27 is free to slide in the socket in the upper end of the rod 26 so that the arm 22 95 can be oscillated from the rock shaft 29 and at the same time the slide 25 can be reciprocated. The shaft 29 is provided with a downwardly projecting arm 30 at its rear end which is provided with a roll engaging a 100 cam on the cam shaft of the machine.

105 The mechanism above described for actuating the looper controls the looper positively in all its movements so that the looper acts with certainty to lay the thread in the 110 barb of the needle regardless of the speed at which the machine is operated. The mechanism is simple in construction and compactly arranged. In operation it has proved to be efficient and durable. This 115 looping mechanism, as so far described, is applicable to inseam shoe sewing machines of types other than that illustrated in the drawings, and is believed to embody features of invention hereinafter set forth in the 120 claims, which are not limited to use in any particular type of inseam shoe sewing machines.

125 In the construction illustrated in the drawings, the slide 25 of the looper mechanism is 130

arranged to reciprocate in a direction inclined to the plane in which the seam is sewed, or in other words, in a direction inclined to the sole of a shoe presented to the machine. This inclined arrangement of the slide is important in a machine employing a thread finger or rin, since it permits the thread finger to be raised higher from the work and causes the thread to be wrapped around the needle more nearly at right angles to the barbed portion. In chain stitch shoe sewing machines that employ a thread arm, the looper passes above the thread engaging portion of the arm before it encircles the needle so as to cause the thread to be engaged by the arm. The distance from the work to which the thread arm can be raised is, therefore, limited by the position of the looper, and when the looper is arranged to operate as has heretofore been customary, the thread arm can not be raised a sufficient distance to avoid contact with the channel flap upon certain classes of work. Furthermore with the thread arm and looper of prior machines, the looper necessarily wraps the thread about the needle at some distance below the barb so that the thread slides down the needle into the barb during the retracting stroke of the needle. By arranging the looper and thread arm as illustrated in the drawings, the thread arm can be raised higher than has heretofore been the custom, and the thread can be laid more nearly directly into the barb of the needle. Greater certainty of the looping operation is thus secured, and also there is less liability of injury to the thread.

The main takeup of the machine is of usual construction and consists of a thread truck 31 mounted upon the forward end of a cam actuated lever 32. The auxiliary takeup consists of a thread truck 33 mounted upon the forward end of a pivoted arm 34. The arm 34 of the auxiliary takeup is pressed upon by a spring actuated plunger 35. This plunger is mounted in a vertical guideway in the frame of the machine, and its upper end is acted upon by a coiled spring 36 seated in a recess in the machine frame between the upper end of the plunger 35 and an adjustable abutment screw 37. The auxiliary takeup is thus spring-pressed, its upward movements being resisted by the tension of the spring 36. The thread, indicated at 38, after passing over the tension wheel at the rear of the machine, passes over a guide truck, 29, then under the truck 33 of the auxiliary takeup, and then over the truck 31 of the main takeup. The arrangement of these trucks is such that during the rising of the main takeup, the auxiliary takeup is moved upward, and during the falling movements of the main takeup the auxiliary takeup is allowed to fall and maintain a tension on the thread determined

by the strength of the spring 36 and the relative positions of the three trucks. The main takeup falls during the thread pulling movement of the thread arm, during the looping movements of the looper, and during the retracting stroke of the needle. To prevent the auxiliary takeup from stealing thread from the thread arm during its loop delivery or forward stroke, and while the needle is making the first part of its retracting stroke, a stop 40 is provided to limit the falling movement of the auxiliary takeup, which stop is engaged by an adjustable abutment screw 41 mounted in the lever 34 of the auxiliary takeup. The stop 40 and 70 abutment screw 41 are so arranged with relation to the falling movement of the main takeup and the thread delivering stroke of the thread arm, that the falling movement of the auxiliary takeup is stopped 75 before the thread arm begins its thread delivering stroke. During the first portion of the falling movement of the main takeup, therefore, and while the needle is being looped, the auxiliary takeup exerts a tension 80 on the thread, but this tension is removed at such time as to prevent any liability of the 85 stealing of thread from the thread arm.

The main takeup of the machine illustrated in the drawings acts in the same manner as that of the machine of Patent No. 412,704 to pull off thread from the supply during its upward stroke and to give up this thread to the needle during its falling stroke to such an extent that the needle will exert 95 a pull on the preceding loop of the seam and shorten this loop. To secure a variation of the pull exerted by the needle on the thread in shortening the preceding loop, the machine illustrated in the drawings is provided with an adjustable stop for limiting the rising movement of the auxiliary takeup, this stop being indicated at 42 and consisting of an adjustable screw threaded 100 abutment screw mounted in the frame of the machine. It will be obvious from an inspection of the drawings, and particularly of Fig. 4, that an adjustment of the stop 42 will vary the amount of thread extending 105 from the looper around the main and auxiliary takeups to the truck 39, and consequently will vary the amount of thread given up by the takeup during its falling movement to the needle.

An adjustment of the stop 42 will obviously vary the time in the operation of the machine at which the abutment 41 of the auxiliary takeup will hit the stop 40 during the falling movement of the auxiliary takeup. The abutment 41 is, therefore, made 110 adjustable so that the falling movement of the auxiliary takeup can be stopped at the desired time in the operation of the machine under any adjustment of the stop 42. This adjustment of the abutment 41 of the 115

auxiliary takeup also permits an adjustment for variation in the operation of the stitch forming devices occasioned by differences in the kind of stock operated upon.

The awl of the machine illustrated in the drawings is indicated at 43, and is secured in the usual manner to an awl carrier 44 pivotally mounted upon the feed slide. The awl is curved in the arc of a circle, of which the pivot of the awl is the center, and during the operation of the machine the awl is oscillated about this center, which remains fixed with relation to the center about which the needle oscillates. The awl is arranged to enter the channel of a shoe and pass through the between substance. To enable the awl to strike at the bottom of the channel and puncture a hole in the between substance in the path of the needle, and at the same time clear the sole at the bottom of the channel, the awl has a radius of curvature less than that of the needle, and the axis about which it oscillates is arranged at the rear of and beneath the axis about which the needle oscillates. The advantages gained by constructing and mounting the awl in this manner will be clearly understood from an inspection of Fig. 19, which illustrates diagrammatically the manner in which the awl engages the work, and the relative paths of movement of the awl and needle. Referring to this figure, it will be seen that the path of movement of the awl is substantially tangent to that of the needle at the point where the awl and needle pass through the work, so that the hole formed by the awl in the between substance will be in line with the needle. It will also be seen that the awl rises from the channel inside of the path which it would travel if it were mounted concentric with the needle, and thus can strike at the bottom of the channel without contacting with the sole back of the channel. In operating upon an insole upper and welt such as are indicated in Fig. 19, an awl mounted to move concentrically with the needle would dig into the sole at the rear of the channel, and in order to cause the awl to strike at the bottom of the channel without engaging the sole back of the channel, it would be necessary to tip the shoe. In tipping, however, the shoe would move about the point of the channel guide as a center, and thereby the welt and the edge of the insole would be raised so that the seam would be placed too low.

By the use of an awl constructed and arranged as illustrated in the drawings, an insole upper and welt such as are indicated in Fig. 19 can be properly sewed, and the seam located in the desired position with relation to the welt and insole. The use of a curved awl mounted to oscillate about a fixed center is advantageous in chain stitch

sewing machines, since the between substance can be completely perforated with a hole concentric with the needle, which cannot be done successfully with other forms of awl, and furthermore the use of a pivotally mounted curved awl permits the use of an extremely simple and compact arrangement of the parts and actuating mechanism. By mounting the awl eccentric to the center of movement of the needle, and moving it on a smaller radius, the use of a curved awl is made practicable, and the disadvantages of prior constructions, in which a curved awl is used, are eliminated.

It is often necessary or desirable in machines of the class to which the present invention relates to adjust the awl to bring its point into the proper position with relation to the needle, which position varies with different needles and different awls. A simple and convenient means for adjusting the awl for this purpose is illustrated in the drawings, and consists of an eccentric 45 formed on the stud 46 which forms the pivot of the awl. This eccentric forms the journal for the awl carrier, and by rotating the stud the awl carrier is raised or lowered to bring the point of the awl into the desired position with relation to the point of the needle.

The channel guide is of usual construction, and is indicated at 47. The channel guide is secured to a block 48, and this block is mounted upon the forward end of the channel guide lever 49 so as to be adjustable vertically thereon. The block 48 is adjusted by means of an adjusting screw 50, and is held in adjusted position by a locking bolt 51 passing through a slot in the block. The channel guide lever 49 is pivotally mounted upon the feed slide, and is actuated by mechanism hereinafter described.

The feed slide of the machine is indicated at 52, and is provided with a cylindrical bore 53, and with an open-sided slot 54 which engage respectively guiding studs 55 and 56 secured to a bracket 57 forming a part of the frame of the machine. This feed slide is provided with bores 58 and 59 for the pivot studs of the awl carrier and channel guide lever, and with a bore 60 for a rocking stud forming a part of the awl actuating mechanism. The feed slide is actuated from a cam on the cam shaft of the machine through a lever 61 pivotally mounted at its forward end and provided intermediate its ends with a slot in which is adjustably secured a block provided with a pin 62 having mounted thereon a block 63 engaging a slot 64 on the feed slide. This connection of the lever and feed slide is of usual construction and permits an adjustment of the length of feed. To enable the feed slide to be adjusted so as to bring the awl in alinement

with the needle at the end of the feeding movement, or into any desired position with relation to the needle, the lever 61 is made separate from its hub and is adjustably secured thereto, the adjustment being effected by an adjusting screw 65 screwed into the side of the lever and having its flanged head in engagement with a slot on the hub, and the lever being secured in this position by a locking bolt 66 passing through a slot in the lever. The hub of the lever 61 is made in the shape of a yoke which extends above and below a bracket 67 secured to the feed slide supporting bracket 57. The hub of the lever 61 is pivoted to the bracket 67 by means of pivot pins extending upwardly and downwardly through the yoke into the bracket and secured in the bracket.

The mechanism for actuating the awl comprises a link 68 connecting the awl carrier with the lower end of a lever 69 which is mounted on the feed slide so as to oscillate and slide longitudinally. The lever 69 is provided at its upper end with a socket which receives a rod 70 projecting downwardly from the end of a rocking stud 71 mounted in the bore 60 of the feed slide. The rod 70 forms a guide upon which the lever 69 can slide longitudinally, and the rocking pin 71 forms a pivot about which the lever oscillates. To oscillate the lever 69 so as to actuate the awl and at the same time permit the lever to move with the feed slide, the lever is provided with a bore which receives a pin 72 projecting laterally from the lower end of a cam actuated bell crank lever 73.

The mechanism for actuating the awl above described is simple and compact in construction as will be apparent from inspection of the drawings. The parts are arranged to move easily and freely, but at the same time are strong enough to prevent breaking or derangement when the machine is operated at high speed.

For moving the channel guide toward and from the work, an easy running, simple and durable construction is provided consisting of a toothed segment or arm 74 meshing 50 with a corresponding tooth on the upper end of the channel guide lever 49, a shaft 75 to which the segment 74 is secured journaled in the bracket 67, and a cam actuated arm 76 secured to the shaft 75.

The back rest of the machine illustrated in the drawings is indicated at 77, and the back rest slide at 78, these parts being constructed and arranged as in prior machines. An improved mechanism for yieldingly supporting the back rest slide is, however, provided, which mechanism is much lighter and quicker acting than the construction commonly used, which comprises a rack and pinion and a clock spring. Another advantage of this improved mechanism is that it

permits the use of a spring which can be easily adjusted, and a spring of such length that the movement of the back rest does not appreciably change the tension of the spring. This mechanism for yieldingly supporting the back rest comprises a horizontal arm 79, the free end of which enters a slot in the back rest and engages a roller 80 mounted therein, and the other end of which is pivotally mounted upon a vertical pivot 75 81. A long coiled spring 82 surrounds the pivot 81, and is connected at its lower end to the arm 79, and at its upper end to a plate or disk 82^a secured to the upper end of the pivot, so as to be capable of adjustment to vary the tension of the spring. The disk 82^a is secured in adjusted position by a clamping screw passing through the disk and screwing into the pivot. The back rest is intermittently locked against backward movement by mechanism hereinafter described.

It is desirable in welt shoe sewing machines that the welt guide move toward and from the shoe in a path substantially concentric with that of the needle, in order that the groove in the welt may be brought into the path of the needle, regardless of the thickness of the material being operated upon. In the construction illustrated in the drawings, this result is secured by mounting the welt guide, which is indicated at 84, upon a welt guide carrying arm 85, and pivoting this arm in front of and above the needle, substantially diametrically opposite the point at which the welt guide engages the work. By so mounting the welt guide, it moves toward and from the work in a path of greater radius than that of the needle, so that it engages the lasting tacks laterally and bends them over, instead of resting upon the heads of the tacks. When in close proximity to the shoe, however, the welt guide is moving in substantially the same path as the needle, so that the groove in the welt is not displaced to any appreciable extent by variation in the thickness of the material operated upon. The welt guide is moved toward and from the shoe at the proper times during the operation of the machine by means of a link 86, a welt guide slide 87 which is connected with the welt guide carrying arm 85 by the link 86, a spring which acts to force the welt guide slide forward, and a cam actuated clutch mechanism which retracts the slide. The spring for forcing the welt guide slide forward is indicated at 88. This spring is coiled around a stud 89 provided with an adjustable cap disk 90 to which one end of the spring is secured. The other end of the spring extends upwardly and bears against a pin 91 projecting from the welt guide slide. The cam actuated clutch mechanism for retracting the slide comprises a clutch 110 115 120 125 130

box 92 surrounding the slide, and provided with inclines between which and the edges of the slide, clutch rolls 93 are located. Coiled springs 94 seated in recesses in the clutch box act upon the rolls and tend to hold them in clutching position against the inclines and the adjacent sides of the slide. The inclines on the clutch box are so arranged that during the rearward movement of the clutch box the slide is gripped by the clutch rolls and the slide is retracted. For actuating the clutch box a cam actuated lever 95 is provided, the lower end of which is connected with the clutch box by a link 96. To positively release the welt guide slide from the clutch rolls 93 during the forward movement of the clutch box, and preferably before the welt guide contacts with the shoe, stationary pins 97 are provided which enter holes in the clutch box as it reaches the limit of its forward movement, and positively force the clutch rolls 93 backwardly against the tension of the springs 94.

It is customary in welt shoe sewing machines to provide means for adjusting the welt guide on its carrier toward and from the path of the needle, so as to bring the grooves of different styles of welt into proper position. To secure this result, the welt guide of the machine illustrated in the drawings is secured to its carrying arm by means of a pivot pin 98 passing through a slot in the arm, and by a stud 99 passing through the arm and provided with an eccentric portion engaging the welt guide.

To lock the back rest slide 78 and the welt guide slide 87 in their forward positions at the proper times during the operation of the machine, the machine illustrated in the drawings is provided with an improved mechanism which is strong and durable, and which acts with certainty to lock the slides precisely in the positions to which they are moved while the slides are unlocked. This mechanism comprises clutch rolls which are arranged to engage suitable friction surfaces on the slides, and which are supported by inclines on a member which is movable from a position in which the rolls are out of engagement with the slides to a position in which the rolls are clutched between the slides and the inclines on the movable member. These clutch rolls, together with their supporting member, constitute friction clutches which are extremely sensitive in operation, and which lock the slides securely in position without liability of any lost motion or any derangement or breakage of the parts. The clutch rolls are indicated at 103 and 104, and are arranged to engage respectively the lower and upper sides of the welt guide and back rest slides. The rolls are arranged in the same vertical plane and are fitted loosely in vertical slots in the frame of the machine.

The supporting member for the rolls is in the form of a wedge indicated at 105, one incline surface of the wedge engaging one roll and the other incline surface engaging the other roll. The wedge 105 is pivotally connected at its rear end to the vertical arm of a bell crank lever 106, the horizontal arm of which is provided with a roll engaging a cam on the cam shaft. The bell crank lever is actuated by the cam to withdraw the wedge to unlock the slides and the wedge is moved in a direction to lock the slides by means of a coiled spring 107 connected at one end to the frame of the machine, and at the other end to the bell crank lever 106.

The machine illustrated in the drawings, while adapted for welted work, can also be used for turned shoes, a suitable back gage of usual construction being substituted for the welt guide, as will be readily understood by those skilled in the art. In such case, the slide 87 will be a back gage slide instead of a welt guide slide, and in fact the slide of welt sewing machines corresponding to the slide 87 of the machine illustrated in the drawings is often termed a back gage slide. Accordingly, in certain of the claims the term "back gage slide" is used to designate the slide 87.

The tension devices of the machine illustrated in the drawings are of well known construction, and comprise a tension wheel 108 at the rear of the machine, a brake disk 109 fast upon the shaft of the tension wheel, a friction brake shoe 110 bearing upon the periphery of the brake disk, a pivoted lever 111 to one end of which the brake shoe is connected, and a spring pressed rod 112 connected to the other end of the lever. For releasing the tension by a backward rotation of the cam shaft when a shoe is to be removed from the machine, the usual throw-off arm 113 is provided, mounted upon the upper end of a bell crank lever 114. To the horizontal arm of this bell crank lever is pivotally connected the upper end of a rod 115 which extends downwardly through a hole in the end of the brake shoe carrying lever 111 and is provided with an adjustable nut 116 arranged to engage the brake shoe carrying lever to move the brake shoe from the friction disk. The rod 115 is pressed upwardly by means of a coiled spring 117.

The heating devices of the machine, illustrated only in part, comprise a steam passage way 118 in the bracket supporting the tension wheel, a vertical steam passage way 119 in the frame of the machine adjacent the looper mechanism, and a plate 120 projecting forwardly from the head of the machine at one side of the main and auxiliary takeup levers. This plate 120 is secured to the head of the machine so as to be capable of lateral adjustment by means of screws 121 passing through a slotted flange of the plate 120.

and screwing into the head of the machine.

The nature and scope of the present invention having been indicated, and a machine embodying the several features of the invention in their preferred form having been specifically described, what is claimed is:—

1. A chain stitch shoe sewing machine, having, in combination, a hook needle, a looper, work feeding means, means for positively actuating the needle through the whole of its retracting stroke to tighten the preceding loop, and means for yieldingly supporting the needle against the pull exerted upon the needle by the thread during the feed.

2. A chain stitch shoe sewing machine, having, in combination, a hook needle, a looper, work feeding means, mechanism for positively retracting the needle to tighten the preceding loop and means for releasing the needle from said retracting mechanism and for supporting it under light spring pressure during the feed.

3. A chain stitch shoe sewing machine, having, in combination, a hook needle, a looper, means for feeding the work, means for actuating the needle to exert a strain on the thread sufficient to tighten the preceding loop, and means for yieldingly supporting the needle during the feed arranged to exert a less strain on the thread.

4. A chain stitch shoe sewing machine, having, in combination, a curved hook needle arranged to pierce the shoe from the outside and emerge from the channel, a looper, and a curved awl movable about an axis eccentric to the needle in a path of smaller radius than that of the needle and substantially tangent to the path of the needle at the point where the needle pierces the work.

5. A chain stitch shoe sewing machine, having, in combination, a curved hook needle arranged to pierce the shoe from the outside and emerge from the channel, a looper, and a curved awl movable about an axis at the rear and below the axis of the needle, said awl moving in a curved path of smaller radius than that of the needle and substantially tangent to the path of the needle at the point where the needle pierces the work.

6. A chain stitch shoe sewing machine, having, in combination, a curved hook needle, a looper, a thread arm, and mechanism for actuating the looper comprising a slide mounted to reciprocate in a right line in a plane parallel to that of the needle and in a direction inclined to the plane in which the seam is sewed, a looper carrying arm pivotally mounted upon the forward end of the slide to oscillate in a plane at right angles to the plane of the needle, and means for reciprocating the slide to move the free

end of the looper across the path of the needle substantially at right angles to said path and means for oscillating the arm to move the free end of the looper across the plane of the needle.

7. A chain stitch shoe sewing machine, having, in combination, a curved hook needle, a looper, a thread arm, and mechanism for actuating the looper comprising a slide mounted to reciprocate above the needle in a right line in a plane parallel to the plane of the needle, a looper carrying arm pivotally mounted upon the forward end of the slide to oscillate in a plane at right angles to the plane of the needle, a rock shaft, connections between the rock shaft and the arm for oscillating the arm to move the free end of the arm across the plane of the needle, means for actuating the rock shaft, and means for actuating the slide to move the free end of the arm across the path of the needle.

8. A chain stitch shoe sewing machine, having, in combination, a curved hook needle, a looper, a thread arm, and mechanism for actuating the looper comprising a slide mounted to reciprocate above the needle in a plane parallel to the plane of the needle, an arm pivotally mounted upon the forward end of the slide to oscillate in a plane at right angles to the plane of the needle and having its ends projecting above and below the slide, means for securing the looper to the lower end of the arm, a rock shaft arranged parallel with the slide, an arm at the forward end of the rock shaft, connections between the arm on the rock shaft and the upper end of the looper carrying arm for oscillating the looper carrying arm, means for oscillating the rock shaft, and means for actuating the slide.

9. A shoe sewing machine, having, in combination, stitch forming devices including a curved hook needle, a feed slide, a curved awl, an awl carrier mounted to oscillate on the feed slide, a lever mounted on the feed slide to oscillate and move longitudinally, a link connecting the free end of the lever and the awl carrier, a cam-actuated bell crank lever, and a connection between the free end of the bell crank lever and said sliding and oscillating lever permitting movement of the sliding and oscillating lever in the direction of feed.

10. A chain stitch shoe sewing machine, having, in combination, a curved hook needle, a looper, and a curved awl movable about an axis eccentric to the needle in a path of smaller radius than that of the needle.

11. A chain stitch shoe sewing machine, having, in combination, a curved hook needle, a looper, a curved awl movable about an axis eccentric to the needle in a path of smaller radius than that of the needle and

means for adjusting the axis of the awl transversely.

12. A chain stitch shoe sewing machine, having, in combination, a curved hook needle, a curved awl mounted to move about an axis fixed with relation to the needle during the operation of the machine, and means for adjusting the axis of the awl transversely.

10 13. An inseam shoe sewing machine, having, in combination, stitch forming devices including a curved hook needle, a feed slide, a channel guide lever carrying the channel

guide pivotally mounted upon the feed slide, and mechanism for oscillating the channel 15 guide lever comprising a segment meshing with the channel guide lever, a rock shaft to which the segment is secured, mounted in stationary bearings, and a cam actuated arm secured to the rock shaft. 20

In testimony whereof I affix my signature, in presence of two witnesses.

ANDREW EPPLER.
